UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed February 20, 1925. Serial No. 10,460.

This invention relates to improvements in stencil-card-writing devices for typewriting machines, and more particularly to the kind disclosed in the patent to Elliot, No. 1,378,771, dated May 17, 1921.

In said patent, there is provided a stencil-card-holding frame pivotally supported at the rear of the carriage and extending over the platen to the front thereof, where there is suspended therefrom a stencil-card. The card is line-spaced by means including a finger-wheel on the card-carrying frame and a cam connected to said finger-wheel, said cam engaging a roller fixedly supported on the carriage-frame. The cam has secured thereto a toothed wheel having a pawl engaging therewith to hold the cam, and consequently the card supported by the card-holder, in various line-space positions. Thus, in operating said device, it is necessary, in order to begin a new line, to return the carriage and operate the line-spacing mechanism, which, in said device, requires two separate operations.

A feature of the present invention relates to improvements to expedite the operation of the device disclosed in said Elliot patent. To this end the carriage is returned and the card line-spaced simultaneously. To bring this about, the line-spacing cam, which raises the card-holder, is supported on the carriage-frame, so as not to have a swinging or bodily movement, and consequently that it may readily be connected with the mechanism ordinarily used to line-space the platen. The roller with which said cam engages, in the present invention, is supported on the card-holder, so that, as the cam is rotated by the actuation of the usual line-space lever, the card-holder is raised to line-space the stencil-card.

The platen may be provided with a celluloid backing, which is carried thereby and remains in position until said backing has become worn, after which the platen may be rotated one line-space position by means of the finger-wheel on the platen-axle. In other words, the platen is not rotated during the line-spacing of the stencil-card. To enable the platen to remain unoperated when the usual line-space lever is actuated, the platen may be provided with the usual clutch shown in the patent to W. F. Helmond, No. 1,150,366, dated August 17, 1915,

by which the platen may be released from its usual line-spacing mechanism.

Provision is also made in the present invention to enable adjustment between the line-spacing mechanism and the cam for raising the card-holder.

Another feature of the invention relates to means comprising a lever by which the line-spacing mechanism may be released so as to allow the card-holder to resume its lowermost position for the beginning of typing of a new stencil-card. This lever may be operated by the card-supporting frame when the latter is raised to its uppermost position.

Other features and advantages will hereinafter appear.

In the accompanying drawings,

Figure 1 is an end view of an Underwood typewriter carriage with portions broken away for clearness, showing the invention applied thereto.

Figure 2 is a diagrammatic view similar to Figure 1 and shows the card-holder raised to its uppermost position to release the line spacing cam.

Figure 3 is a diagrammatic side view showing the line-spacing mechanism operated.

Figure 4 is a top plan view of the device.

Figure 5 is a fragmentary front view showing the line-spacing mechanism.

Figure 6 is a fragmentary side view showing the line-spacing cam and a pawl-and-ratchet for holding it in its operated positions.

A stencil-card 10 upon which it is desired to type one or more lines of data is inserted between the jaws 11 of a clamping member 12, which is pivotally mounted upon a shaft 13 on a rocking frame 14 which is in turn rockably mounted on a cross-shaft 15 fast on the platen-frame 16 of a typewriting machine. The clamping member 12, as it is shown in the drawings, consists of a sheet-metal bail having a finger-piece 17 at the center, and the jaws 11 being formed at the ends and joined by a connecting piece 18. The jaws hold the card in a locating recess formed in the end plates 19 of the rocking frame 14 which are joined together by a connecting bar 20. The finger-piece 17 cooperates with another finger-piece 21, the latter being fastened to the frame 14 by means of a cross-bar 22 of which it forms an integral part. The two finger-pieces are

drawn together to open the jaws against the pressure of springs 23, while at the same time the frame may be lifted to the position shown in Figure 2 against a stop device 24.

5 Then the finger-piece 17 is released to clamp the card, and the frame is lowered to typing position as shown in Figure 1.

To facilitate the lowering of the card 10 there is provided a deflector plate 25 which 10 is also designed to hug the card against the platen to prevent shadowing of the types in a case position not being imprinted upon the card. One of the type-bars, designated by the numeral 26, is shown in front of the 15 platen which serves as a backing for the card when the types are struck to cut the stencil-card. Thus, by successively striking the types and by line-spacing the carriage after each impression, the first line of typing 20 is written upon the card.

In order to line-space the card there is provided mechanism whereby the free end of the rocking frame 14 may be raised amounts corresponding to the space between 25 the lines. Said mechanism is operatively connected to the line-space lever 27 of an Underwood standard machine, which is operated simultaneously with the return of the carriage. Said mechanism comprises a pawl 30 30 28 and a ratchet 29, the former being pivotally mounted by means of a screw 30 on the slide 31 of the Underwood line-space mechanism. The pawl is resiliently held against the ratchet by means of a spring 32 35 also fast upon the slide 31 by means of a screw 33. When the carriage is returned the slide 31 is moved rearwardly and the ratchet 29 is rotated one tooth by the pawl 28. Said ratchet 29 is mounted upon a shaft 40 34, which is revolvably mounted on brackets 35 fast to the platen-frame by means of screws 36. In order to render the ratchet-and-pawl arrangement operative there is provided a retaining ratchet 37 co-operating 45 with a pawl 38, the latter being mounted on a cross-shaft 39 which is supported by the platen-frame 16 while the former is connected to the ratchet 29 by means of a connecting hub 40 of which it forms an integral 50 part. As the ratchets are rotated, a cam 41 is simultaneously driven around with the ratchets, and, due to its peculiar periphery, the cam raises the frame by engaging a roller 42 which is rotatably mounted on said frame. 55 In this manner, the card is raised, each time that the ratchet 29 is spaced one tooth, an amount equivalent to the width of one space between two lines of typing upon the card.

When typing upon cards used in connection with addressing machines, it is sometimes necessary to use two, three or four lines and due to its limited space it is desirable to space the lines according to the number of lines to be typed thereon. To this end, the retaining ratchet 37 is provided

with three sets of teeth each having a plurality of teeth equally spaced, but each set having teeth of a different pitch. In order that the ratchet may be quickly positioned to correspond to the desired number of lines 70 upon the card, the cam is fast on the shaft 34, and the ratchet 37 is provided with a pin 43 engaging with holes 44 in the cam 41. When it is desired to change the position of the ratchet relatively to the cam, the pin 75 43 is pulled out of engagement with one of the holes 44 by drawing the ratchet against a spring 45 wound around the shaft 34 and the ratchet is rotated relatively to the cam. In this manner a different set of teeth may 80 be brought into position to co-operate with the feed and retaining pawls.

After each line of typing, the carriage is restored and the pawl 28 is moved to feed one tooth of the ratchet 29. As the ratchet 85 is fed around, however, a spring 46 is wound, thus storing up power to rotate the ratchet backwardly when the retaining pawl 38 is released. Said spring 46 is held at one end by a pin 47 on the shaft, and at the other 90 end is supported against one of the brackets 35. To eliminate the necessity of manually releasing the pawl 38 to return the cam 41 to its normal position corresponding to the first line of typing upon the card, the pawl 95 38 is provided with an extension 48 in the path of a pin 49 fast on the frame 14. When the frame is raised to insert a fresh card in the jaws, the pin 49 strikes the extension 48 and releases the pawl 38 so as to clear 100 the teeth 50 of the ratchet 37. Then, due to the action of the spring 46, the cam and the ratchets fly back to their normal position against a pin 51 fast on a center bracket 52 and against which a flat portion 53 of the 105 cam 41 strikes.

It is customary to provide a back for the stencil-cards, in order to prevent the type blows from injuring the platen and to facilitate the cutting of the stencil. A backing 110 54, generally made of celluloid or other hard material, is held on the platen 55 in a position to be struck by the types. Said backing encircles a portion of the platen and is held in place by means, not shown, but it may include a plate in the manner disclosed in the application of Alfred G. F. Kurowski, Serial No. 746,951, filed October 31, 1924. As it is desired to hold the celluloid 115 backing stationary, so that the same portion may be used and then line-space the platen to bring a fresh portion into the printing field, the platen of the machine is disconnected from the carriage-return lever. To this end the clutch button 56, usually found in the Underwood machines, is pulled outwardly and thus the platen-shaft 57 is disconnected from the line-space mechanism, rendering the platen stationary. The platen may be spaced in the usual way 120 125 130

by a hand-wheel 58 which is fast to the platen-shaft.

Variations may be resorted to within the scope of the invention, and portions of the 5 improvements may be used without others.

Having thus described my invention, I claim:

1. A device for typing stencil-cards, including, in combination, a platen, a carriage 10 therefor, a carriage-return lever, an elevatable frame overlying the platen, said frame being pivotally mounted upon the carriage at the rear of the platen and having means for supporting a stencil-card pendent therefrom, said card contacting with the platen at the printing line, and means controlled by the carriage-return lever, for elevating the free end of the frame step by step to successively line-space the card, said means including a cam-plate rotatably mounted on a supporting member fixed relatively to said carriage, and said elevatable frame having means to engage the came to lift the frame step by step as the cam rotates.

25 2. A device for typing stencil-cards, including, in combination, a platen, a carriage therefor, a carriage-return lever, a frame having means for suspending a card presented to the platen at the printing line thereof, 30 said frame being hinged on said carriage at the rear thereof, and means for elevating the free forward end of the frame to line-space the card upon operation of the carriage-return lever, said elevating means including a 35 cam pivotally mounted on a shaft, fixed relatively to the carriage, a ratchet mounted on said shaft, a pawl reciprocated by the carriage-return lever, said pawl engaging with the ratchet, retaining means for said ratchet, 40 and means carried by said frame for engaging the cam in a manner to elevate the frame step by step as the cam rotates.

3. In combination with a typewriting machine including a carriage and a platen 45 therefor, a line-space mechanism operatively connected to a carriage-return lever, a stencil-cutting mechanism comprising a rockably mounted frame disposed to present a stencil-card to the printing field in front of the platen, means whereby the platen may be 50 disconnected from the carriage-return lever, and means controlled by the carriage-return lever to line-space the stencil-card, said last-mentioned means including a cam revolvably mounted on a shaft fixed relatively to the platen, and a roller on said frame operatively connected to the cam.

4. In combination with a typewriting machine including a carriage and a platen 60 therefor, a line-space mechanism operatively connected to a carriage-return lever, a stencil-cutting mechanism comprising a rockably mounted frame disposed to present a stencil-card to the printing field in front of the platen, means whereby the platen may

be disconnected from the carriage-return lever, means controlled by the carriage-return lever to line-space the stencil-card, said last-mentioned means including a cam revolvably mounted on a shaft fixed relatively to the 70 platen, and a roller on said frame operatively connected to the cam, and means to protect the platen against the type blows, said last-mentioned means including a celluloid backing encircling the platen and fastening means to hold the backing around the platen.

5. In combination with a typewriting machine including a carriage and a platen therefor, a line-space mechanism operatively connected to a carriage-return lever, a stencil-cutting mechanism comprising a rockably mounted frame disposed to present a stencil-card to the printing field in front of the platen, means whereby the platen may be 80 disconnected from the carriage-return lever, means controlled by the carriage-return lever to line-space the stencil-card, said last-mentioned means including a pawl operatively connected to the carriage-return lever, a 85 ratchet co-operating with said pawl, a retaining ratchet and a pawl therefor, the two ratchets being joined together by a connecting hub, and both being operatively connected to a cam to drive the same around, a roller mounted on the frame and co-operating with the cam to raise the frame to positions corresponding to different line-spacing widths, and means whereby the relative positions of the cam and the ratchets may be 90 changed to postions corresponding to the line-spacing width of the card.

6. In combination with a typewriting machine including a carriage and a platen therefor, a line-space mechanism operatively connected to a carriage-return lever, a stencil-cutting mechanism comprising a rockably mounted frame disposed to present a stencil-card to the printing field in front of the platen, means whereby the platen may be 100 disconnected from the carriage-return lever, means controlled by the carriage-return lever to line-space the stencil-card, said last-mentioned means including a pawl operatively connected to the carriage-return lever, a 105 ratchet co-operating with said pawl, a retaining ratchet and a pawl therefor, the two ratchets being joined together by a connecting hub, and both being operatively connected to a cam to drive the same around a roller mounted on the frame and co-operating with the cam to raise the frame to positions corresponding to different line-spacing widths, and means whereby the relative position 110 of the cam and the ratchets may be changed to positions corresponding to the line-spacing width of the card.

115 7. In combination with a typewriting machine including a carriage and a platen therefor, a line-space mechanism operatively connected to a carriage-return lever, a stencil-cutting mechanism comprising a rockably mounted frame disposed to present a stencil-card to the printing field in front of the platen, means whereby the platen may be 120 disconnected from the carriage-return lever, means controlled by the carriage-return lever to line-space the stencil-card, said last-mentioned means including a pawl operatively connected to the carriage-return lever, a 125 ratchet co-operating with said pawl, a retaining ratchet and a pawl therefor, the two ratchets being joined together by a connecting hub, and both being operatively connected to a cam to drive the same around a roller mounted on the frame and co-operating with the cam to raise the frame to positions corresponding to different line-spacing widths, and means whereby the relative position of the cam and the ratchets may be changed to positions corresponding to the line-spacing width of the card, means to release the retaining pawl simultaneously with the insertion of a fresh card, said last-mentioned means including a spring which is wound 130

- during the line-spacing feed, and an extension on the retaining pawl striking a pin in the frame when the frame is moved to its reloading position.
5. 7. In combination with a typewriting machine including a carriage, a platen therefor, and a carriage-return lever, a stencil-cutting device borne by the carriage disposed to present a stencil-card to the printing field in front of the platen, said stencil-cutting device comprising a rockably mounted card-carrying frame and clamps therefor to hold the edge of the card, a cam rotatably mounted on the carriage and fixed relatively to the platen, a roller on the card-carrying frame operatively connected to the cam to raise the free end of the frame as the cam is rotated, and means operatively connected to the carriage-return lever for rotating the cam simultaneously with the spacing of the carriage.
10. 8. In combination with a typewriting machine including a carriage, a platen therefor, and a carriage-return lever, a stencil-cutting device borne by the carriage disposed to present a stencil-card to the printing field in front of the platen, said stencil-cutting device comprising a rockably mounted card-carrying frame and clamps therefor to hold the edge of the card, a cam rotatably mounted on the carriage and fixed relatively to the platen, a roller on the card-carrying frame operatively connected to the cam to raise the free end of the frame as the cam is rotated, and means operatively connected to the carriage-return lever for rotating the cam simultaneously with the spacing of the carriage, said means including a pawl-and-ratchet arrangement operated by the carriage-return lever, and a retaining ratchet operatively connected to a retaining pawl.
15. 9. In combination with a typewriting machine including a carriage, a platen therefor, and a carriage-return lever, a stencil-cutting device borne by the carriage disposed to present a stencil-card to the printing field in front of the platen, said stencil-cutting device comprising a rockably mounted card-carrying frame and clamps therefor to hold the edge of the card, a cam rotatably mounted on the carriage and fixed relatively to the platen, a roller on the card-carrying frame operatively connected to the cam to raise the free end of the frame as the cam is rotated, and means operatively connected to the carriage-return lever for rotating the cam simultaneously with the spacing of the carriage, and means controlled by the swing of the card-carrying frame to restore the cam to its normal position corresponding to the first line of typing upon the stencil-card, simultaneously with the raising of the card-frame to insert a fresh card.
20. 10. In combination with a typewriting machine including a carriage, a platen therefor, and a carriage-return lever, a stencil-cutting device borne by the carriage disposed to present a stencil-card to the printing field in front of the platen, said stencil-cutting device comprising a rockably mounted card-carrying frame and clamps therefor to hold the edge of the card, a cam rotatably mounted on the carriage and fixed relatively to the platen, a roller on the card-carrying frame operatively connected to the cam to raise the free end of the frame as the cam is rotated, and means operatively connected to the carriage-return lever for rotating the cam simultaneously with the spacing of the carriage, and means controlled by the swing of the card-carrying frame to restore the cam to its normal position corresponding to the first line of typing upon the stencil-card, simultaneously with the raising of the card-frame to insert a fresh card.
25. 11. A device for typing stencil-cards, including, in combination, a platen, a carriage therefor, a carriage-return lever, a frame having means for supporting a stencil-card pendent therefrom, said frame being pivotally mounted on the carriage in a manner to overlie the platen and to present the card to the platen contacting therewith at the printing line, and means for elevating the forward free end of the frame step by step to line-space the card, said elevating means including a cam rotatably mounted on a shaft fixed relatively to the carriage, a roller carried by said frame, said roller contacting with the cam to elevate the frame step by step when the cam is rotated, and means controlled by the reciprocating movement of the carriage-return lever for rotating the cam, said last-mentioned means including a ratchet fixed to the cam, a pawl reciprocated by the carriage-return lever, said pawl being designed to normally clear the ratchet but to engage the same upon operation of the carriage-return lever, a retaining ratchet also fixed relatively to the cam, a retaining pawl pivotally mounted on the carriage, said retaining pawl being releasable when the frame is manually elevated to attach a fresh card thereto, and a spring for returning the cam to its normal position upon clearing the retaining pawl.

JESSE A. B. SMITH.
